UNITED STATES PATENT OFFICE

2,174,327

SCREW DRIVER

Eugene S. Love, Newnan, Ga.

Application June 30, 1938, Serial No. 216,798

1 Claim. (Cl. 145—50)

This invention relates to screw drivers, and an object of the invention is to provide a screw driver, the blade or bit of which may be readily adjusted longitudinally with respect to the handle of the tool as found desirable.

A further object of the invention is to provide a screw driver of the character above mentioned wherein the headed screw or similar work may be placed and magnetically held preparatory to being rotated in securing it to an object.

The invention together with its objects and advantages will be best understood from a study of the following description taken in connection with the accompanying drawing wherein:

15 Figure 1 is a longitudinal sectional view through the screw driver with certain parts shown in elevation.

Figure 2 is a horizontal sectional view taken substantially on the line 2—2 of Figure 1, and

20 Figure 3 is a fragmentary detail sectional view taken substantially at right angles to Figure 1, and at the blade or bit-equipped end of the tool.

Referring to the drawing by reference numerals it will be seen that the screw driver in the preferred embodiment thereof comprises a handle 5 of wood or other suitable material that is provided with an axial bore 6 and is equipped at one end with a metallic ferrule or cap 7 for strengthening and reinforcing purposes.

30 The bore 6 accommodates therein a shank 8 that is provided with a threaded pin 9 on which is threaded a cap nut 10 that seats within a socket provided therefor in the outer or free end of the handle 5 and serves to secure the shank 8 in positive association with the handle 5.

35 At the end thereof remote from the pin 9 shank 8 is provided with an integral fork 11 the legs 12 of which are in closely spaced parallelism and at their terminals 13 are magnetized in a manner to provide a permanent magnet so that when engaged with the head of a screw or the like 14 the latter will be held in place, magnetically, preparatory to being rotated in securing it to an object.

40 The legs 12 of the fork 11 slidably accommodate therebetween the blade or bit 15, the term "bit" as here used referring particularly to a screw driver bit or blade but may of course include all forms of replaceable hand tool elements 50 that may be connected to the handle tool 5.

The bit or blade 15 is substantially flat and is provided on opposite sides thereof with longi-

tudinal ribs or keys 16 that are accommodated in longitudinal grooves or ways 17 provided on the inner sides of the legs 12 of fork 11 as will be clear from a study of the drawing. Thus the bit 15 is held between the legs of the fork 11 in a manner constraining the bit or blade to shift longitudinally relative to the fork.

The opposite longitudinal edges of the bit or blade 15 are provided with threads 18 that complement the threads of an adjusting nut 19 that is engaged in grooves 20 provided in the outer sides of the legs 12 of the yoke 11. Obviously by rotating the nut 12 the bit 15 may be projected or retracted relative to the fork or yoke 11.

Also, in accordance with the present invention the working head of the blade or bit 15 has the opposite sides thereof knurled or otherwise formed to provide roughened surfaces 21 that will engage the contacting metal of the screw head and effectively stop longitudinal motion of the bit or blade relative to the screw and thus overcome the tendency of the blade or bit to "lift out" of the kerf in the head of the screw as sometimes occurs when twisting force is applied to the screw driver and as is necessary in securing the screw to the object or work.

It is thought that a clear understanding of the construction, utility and advantages of a screw driver embodying the features of the present invention will be had without a more detailed description.

Having thus described the invention what is claimed as new is:

In a screw driver, a handle, a fixed holder extending from the handle and comprising a pair of parallel laterally spaced legs provided in the inner faces thereof with a pair of opposed longitudinal grooves, extending from end to end thereof, and a pair of opposed transverse circumferential grooves intermediate said ends, a nut rotatably mounted in said transverse grooves, and a bit of substantially the same length as said legs slidably fitted therebetween and provided with a reduced flat working end and longitudinal keys fitting into said longitudinal grooves and extending from said reduced end to the opposite end of the bit, said bit having threaded side edges extending outwardly of said legs for engagement with the threads of said nut, the outer ends only of said legs being magnetized.

EUGENE S. LOVE.
